DIE CASTING MACHINE

Torbjorn C. Korsmo, Madison, Wis., assignor to
 Madison-Kipp Corporation, Madison, Wis., a
 corporation of Wisconsin

Application April 16, 1934, Serial No. 720,905

12 Claims. (Cl. 22—70)

This invention relates to the art of metal casting and more particularly, to machines for manufacturing die castings.

In the type of die casting machine to which the present improvements are directed, a melting pot is provided in which is mounted a pressure chamber or goose neck. Molten metal in the melting pot is permitted to flow into the pressure chamber, preferably through a suitable port or ports therein. Following this, ejecting means, generally in the form of a plunger located in the metal receiving end of the pressure chamber and controlling the metal inlet port, are brought into action to eject the metal from the discharge end of the pressure chamber into a die associated therewith.

Heretofore, in the center-gated type of machine with stationary pressure chamber and die arranged for horizontal movement, the pressure chamber has been arranged so that the discharge portion thereof is above the level of the metal in the melting pot. This leaves considerable space between the metal in the pressure chamber and the die from which air is forced into the die each time a casting is made. Obviously, entry of this large quantity of air into the die with the molten metal results in the production of defective castings. Frequently also, freezing of the molten metal in the pressure chamber is caused by chilling of the discharge end thereof.

An important object of this invention is to provide for reducing to a minimum the amount of air forced into the die from the pressure chamber.

A further important object is to provide for mounting the pressure chamber in the melting pot so as to permit such free movement of the pressure chamber as is desirable because of variations in the size of the pressure chamber due to temperature changes therein.

Another important object is to provide dress excluding means for the inlet port or ports in the pressure chamber.

Other objects and advantages of the invention will appear from the following detailed description and accompanying drawing, in which:

Fig. 1 is a front elevation of a portion of a die casting machine with the present improvements applied thereto;

Fig. 2, a central longitudinal section through the melting pot, the pressure chamber, and the die;

Fig. 3, a transverse section through the melting pot and the plunger end of the pressure chamber; and

Fig. 4, a perspective of the end of the melting pot which supports the discharge end of the pressure chamber.

In the drawing, the frame of the machine is represented at 6 and carries a hot plate 7 on which is removably secured the stationary part 8 of a center-gated die. The movable half of the die is shown at 9, and 11 (Fig. 1) indicates the operating means therefor. These means may be either of the manual or power type and are not shown since they do not comprise a part of the present invention.

At 12 there is shown the furnace in which is supported the melting pot 13. The furnace 12 opens at its under side into a housing 14 in which is located any suitable heating means (not shown) for the metal in the melting pot. Housing 14 is formed with a flange 16 through which project bolts 17 having nuts 17', for securing the housing to furnace 12. A bracket 18 secured to main frame 6 carries adjustable supporting means 19 which serve in part to support the furnace and burner-housing assembly described.

Melting pot 13 is supported in furnace 12 by means of a horizontal flange 21 around the upper edge of the melting pot which rests upon the upper edge 22 of the furnace. Furnace 12 is cut away at 23 (Fig. 1) to accommodate the extension 24 forming the end of the melting pot.

Mounted in melting pot 13 is a pressure chamber or goose neck 26 which, preferably, is of the type having an upright, metal-receiving portion 27, an inclined portion 28, and a substantially horizontal, metal discharge portion 29. Melting pot 13 has a notch 31 in its upper edge through which extends the metal outlet portion 29 of the goose neck. Notch 31 has an arc-shaped, tapering groove 32 in which rests a correspondingly shaped rib 33 formed on goose neck discharge portion 29. In order to support the opposite end of the goose neck, the metal-receiving portion 27 thereof is formed at each side with an inclined arm 34, the outer end portion 36 of which extends over and rests upon the upper edge 31 of the melting pot.

Goose neck 26 has a continuous passage extending therethrough. In the portion of this passage which is located in the metal-receiving section 27 of the goose neck, there is fitted a sleeve 38 provided near its lower end with a port 39 opening into the inclined portion 41 of the goose neck passage. Sleeve 38 and the goose neck are provided with registering openings which provide a pair of diametrically opposed metal

inlet ports 42, 43 near the top of the metal-receiving portion 27 of the goose neck.

Inlet ports 42, 43 are located immediately below goose neck supporting arms 34, 34, which latter are of inverted U-shape in cross section (see Fig. 1) so as to provide depending flanges 44, 46 extended downwardly at their lower ends on either side of the ports. There is thus provided by each supporting arm 34 an inclined channel 47 into which the corresponding metal inlet port opens and which channel extends upwardly to a point above the top of the melting pot. Each arm 34 also has a horizontal groove 47' to facilitate flow of the metal into the inlet port from the under side of the arm. With this arrangement, adequate means are provided for excluding entry of dross into the goose neck through metal inlet ports 42, 43. Even though the metal level in the pot should drop considerably below the point at which it is normally maintained, i. e., substantially at the upper edge of the melting pot, the means described would function effectively to perform their purpose.

Arranged for reciprocation in sleeve 38 is a metal ejecting plunger 48, shown in Figs. 2 and 3 in its elevated position. At this time ports 42, 43 are open to permit metal from the melting pot to fill the goose neck. Following this the plunger descends to close ports 42, 43 and force the metal from the goose neck into the closed die. The mechanism for operating plunger 48 is adapted to be mounted in a supporting member 49 attached to the top of melting pot 13. This operating mechanism, which may be of the manual or power type, forms no part of the present invention and, therefore, is not shown, nor, for sake of clearness, is the plunger 48 shown in Fig. 1. Member 49 is provided with front and rear flanges 51, only one of which is shown. These flanges and flange 21 on the melting pot are correspondingly perforated to receive bolts 52 extending from furnace 12 and having nuts 51', whereby all of these parts are rigidly secured together. Bolt and nut means 53 also serve further to secure the melting pot to the furnace.

Supporting member 49 has a notch 54 at the die end thereof to accommodate the outlet portion 29 of the goose neck. A set screw and lock nut device 56 mounted in supporting member 49 at this point engages the upper side of outlet portion 29 of the goose neck so as to securely maintain sealing engagement between groove 32 in the melting pot and rib 33 on the goose neck. In this manner, any possible leakage of molten metal from the melting pot at this point is prevented.

Supporting member 49 has notches 57 to accommodate the supporting portions 36 of arms 34. A set screw and lock nut device 58 is mounted in member 49 at each of these notches and engages arm portion 36 to prevent vertical movement thereof. However, each notch 57 is wider than arm portion 36, so that said arm portion is free to move horizontally, provided set screw 58 is not set too tightly. With the described arrangement, it will be noted that the metal discharge portion of the goose neck is anchored to the melting pot, but the supporting arms 34 of the goose neck may move horizontally to compensate for variations in the length of the goose neck due to temperature changes therein.

As shown in Figs. 1 and 2, front and back plates 59, 60 extend from hot plate 7. Projecting inwardly from each of plates 59, 60 is a stub shaft 75 upon which is pivotally mounted a lever 62 in-

termidate its ends. The upper end of each lever 62 carries a set screw and lock nut device 63, the inner end of which engages hot plate 7. The lower end of lever 62 has a hook 64 which engages a notch 65 in a lug 66 formed on supporting member 49 at one side of the discharge portion of the goose neck. Hook 64 on the other lever 62 engages a similar lug 66 (not shown) on the other side of the goose neck outlet. In this manner, the combined furnace, melting pot, and goose neck assembly is supported in proper relation to hot plate 7 and the die.

Inclined portion 41 of the passage through the goose neck communicates at its upper end with a horizontal connecting portion 67 which extends to the exterior of the melting pot. Here portion 61 communicates through an upwardly inclined portion 68 with a horizontal metal outlet portion 69. Mounted in stationary die part 8 is a nozzle 71 having a reduced portion projecting through an opening 72 in hot plate 7 and formed with a tapered end 73 having sealing engagement with the outlet portion 69 of the goose neck. A passage 74, having a restricted portion 75, extends through nozzle 71 and opens at its outer end centrally of the discharge portion 69 of the goose neck passage. At its opposite end, passage 74 feeds into the die cavity 76. It will be clear that the set screw devices 63, 63 may be adjusted in order to insure sealing engagement between the goose neck outlet and nozzle 71.

As indicated by the dot and dash line A in Fig. 2, the goose neck 26 is so designed and mounted in the melting pot that the longitudinal axis of goose neck outlet 69 and also that of passage 74 in nozzle 71 are substantially on the same level as the upper edge of melting pot 13. Since the melting pot in operation is substantially full, the surface of the metal in goose neck outlet 69 is substantially at the level of the axis thereof, but not sufficiently high to overflow past the restricted portion 75 of passage 74 in nozzle 71. In this manner, substantially half the volume of goose neck outlet 69 is filled with molten metal. Horizontal portion 67 of the goose neck passage is arranged at a lower level, so that it is almost entirely filled with metal. Thus, the air space normally present in the outlet end of the goose neck, and consequently the volume of air forced into the die at each casting operation, is materially reduced. As a result, much better castings have been produced with the described arrangement than has been possible heretofore. Also, by reason of the presence of the molten metal in the outlet portion of the goose neck, the objectionable freezing of the goose neck at this point is eliminated.

What is claimed is:—

1. The combination in a die casting machine of a melting pot; and a pressure chamber in the melting pot, said pressure chamber having a metal discharge end fixedly supported by the melting pot, the opposite end of the pressure chamber being supported by the melting pot so as to permit variations in the size of the pressure chamber due to temperature changes therein.

2. The combination in a die casting machine of a melting pot; and a horizontally disposed pressure chamber in the melting pot, said pressure chamber having a plurality of connections to the metal pot, one of which is fixed and the remainder of which are adapted only for substantially horizontal automatic adjustment to compensate for variations in the size of the

pressure chamber due to temperature changes therein.

3. The combination in a die casting machine of a melting pot; a pressure chamber in the melting pot, said pressure chamber having a metal discharge end supported by the melting pot; supporting arms extending from the opposite end of the pressure chamber to the melting pot; releasable means for fixedly securing the discharge end of the pressure chamber to the melting pot; and releasable means for securing said arms to the melting pot so as to permit only horizontal movement of the arms.

4. The combination in a die casting machine of a melting pot having a notch in its upper edge provided with a groove; a pressure chamber mounted in the melting pot, said pressure chamber having a metal discharge end provided with a rib, the discharge end of the pressure chamber resting in said notch with the rib in said groove; releasable means for securing said rib and groove in sealing engagement; supporting arms extending from the opposite end of the pressure chamber and having their outer ends slidably supported on the upper edge of the melting pot; and releasable means for preventing vertical movement of said arms.

5. The combination in a die casting machine of a melting pot; a pressure chamber mounted in the melting pot and having a metal inlet port; and a supporting member extending to the melting pot from the pressure chamber at a point above said port, whereby said member serves to prevent entry of dross into the port.

35 6. The combination of claim 5 further characterized in that said supporting member is provided with depending, dross-excluding portions located at the sides of said port.

7. The combination of claim 5 further characterized in that said supporting member is formed with a channel on its under side into which said port opens, said channel being inclined upwardly and away from said port.

8. A pressure chamber for use in a die casting machine melting pot comprising a body includ-

ing a metal discharge portion and an upright metal-receiving portion having a metal inlet port in the upper part of the side wall thereof, said pressure chamber being provided with dross-excluding means constructed and arranged adjacent the inlet port so that said port may have substantially horizontal, free communication directly with the interior of the melting pot.

9. The pressure chamber structure of claim 8 further characterized in that said dross-excluding means are in the form of a hood surrounding the top and sides of the inlet port.

10. The combination in a die casting machine of a stationary melting pot; and a pressure chamber provided with a passage therein having an upwardly inclined portion, a horizontal connecting portion, a second upwardly inclined portion and a horizontal discharge portion, all adjoining and arranged in the order recited, said pressure chamber being mounted in the melting pot so that the longitudinal axis of the discharge portion of said passage is substantially at the level of the top of the melting pot.

11. The combination in a die casting machine of a melting pot; a removable pressure chamber located in the melting pot and having a metal discharge portion projecting through the melting pot below its upper edge; and releasable means for effecting sealing engagement between the melting pot and the discharge portion of the pressure chamber.

12. The combination in a die casting machine of a stationary melting pot; and a pressure chamber in the melting pot having a discharge end projecting outwardly through a wall of the melting pot and provided with a passage having a horizontal portion extending to the exterior of the melting pot, substantially all of said horizontal portion being below the level of the top of the melting pot, said passage outside of the melting pot forming a horizontal discharge portion located with its longitudinal axis substantially at the level of the top of the melting pot.
